COMPRESSOR CONTROL SYSTEM

Charles E. Finley, Derry, Pa.

Application September 21, 1945, Serial No. 617,813

2 Claims. (Cl. 230—4)

1

This invention relates to locomotive carried air compressing apparatus for supplying compressed air to locomotive and train brakes, and more particularly to check valve and compressor unloader valve components for such apparatus.

In the normal operation of locomotive air compressors, after a period of service the outlet valves of the compressor become worn or otherwise defective, so that they leak slightly and permit compressed air from the air storage tank to leak back into the compressor cylinders. As the first stage of the compressor is designed to operate on air at atmospheric pressure and increase the pressure of such air to a value approximately half way between atmospheric and tank pressure, leakage of highly compressed air from the storage tank into the first stage cylinder will develop an air pressure in such cylinder sufficient to stall the first stage steam cylinder and thus discontinue operation of the compressor.

When this occurs it is necessary, at present, to remove the compressor from the engine for over-haul even though the leaky outlet valves constitute only a small defect and the compressor is otherwise capable of an extended period of further service before overhaul.

It is therefore among the objects of the present invention to provide an improved air compressing apparatus for locomotive and train brakes of such character that the steam operated air compressor may be continued in service on the locomotive for an extended period after the outlet valves of the compressor start to leak, to install an effective check valve between a locomotive carried air compressor and an associated air storage tank to substantially preclude leakage of air from the storage tank back into the compressor, and to install between the compressor and such check valve a compressor unloading valve operated by the compressor governor to vent all compressed air from the compressor when operation of the compressor is discontinued by the compressor governor, which check valve and unloader valve are of simple and durable construction, are easy to install without material modification of the compressor or compressor governor, and are effective to prevent stalling of the compressor before sufficient wear has taken place throughout the compressor to necessitate removal of the compressor from the engines for complete over-haul.

Other objects and advantages will become apparent from a consideration of the following description and the appended claims in conjunction with the accompanying drawing wherein:

2

Figure 1 is a diagrammatic, cross-sectional illustration of locomotive carried air compressing apparatus illustrative of the invention; and

Figure 2 is a transverse cross-section of the check valve component of the apparatus, taken substantially on the line 2—2 of Figure 1.

With continued reference to the drawing, the apparatus comprises, in general, a conventional steam operated air compressor 10, an air storage tank 11, pneumatically connected with the compressor outlet by a pipe line 12, a steam valve 13 connected at one end to the locomotive boiler and at its opposite end to the steam inlet of the compressor 10 by a pipe line 14, a compressor governor 15 operatively connected with the valve 13 and pneumatically connected by pipe lines 16 and 17 with the air storage tank 11, a check valve 18 interposed in the pipe line 12 between the compressor outlet and the air storage tank 11, and a compressor unloading valve 19 pneumatically connected by the conduit 20 to the pipe line 12 between the check valve 18 and the compressor outlet and by a conduit 21 to the compressor governor 15.

The compressor 10 may be anyone of several known forms of two stage, steam operated air compressors mounted on railway locomotives to supply compressed air for the locomotive and train brakes. The governor illustrated has a first stage steam cylinder 22 in which a steam piston 23 is reciprocable and a first stage air compressing cylinder 24 in which a first stage air compressing piston 25 is reciprocable. The pistons 23 and 25 are rigidly connected together by a partly tubular piston rod 26 which extends slidably through the top of the air compressing cylinder 24 and through the bottom of the steam cylinder 22. The adjacent end of the steam pipe 14 is connected to the steam inlet fitting 27 of the compressor and a steam channel 28 leads to the piston operated slide valve 29 and to the steam operated piston valve 30 which controls the application of steam at boiler pressure to the opposite sides of the steam piston 23.

The first stage air compressing cylinder 24 is equipped with two air intake strainers 31 disposed at respectively opposite ends of the cylinder and two similarly disposed air intake valves 32 for admitting air at atmospheric pressure into the first stage cylinder. As the first stage air compressing piston 25 works upon air admitted at atmospheric pressure and as the first stage steam piston 23 is acted upon by steam at boiler pressure, the piston 25 is much larger than the piston 23 in order to initially compress a large

volume of air by an economical quantity of steam. Under these conditions, if air should leak from the storage tank 11 through the compressor outlet valves back into the first stage cylinder 24 and build up a pressure in this cylinder slightly above the delivery pressure of the first stage cylinder of the compressor, the steam piston 23 would have insufficient area to move the air compressing piston 25 and the compressor would stall since the valve 29 could not then be operated. The slide valve 29 is connected to the piston rod 26 by a valve rod 33 having a headed end received in the bore of the partly tubular piston rod so that the slide valve is moved from one to the other of its two operated positions as the pistons 23 and 25 approach the opposite ends of their stroke. The slide valve 29, controls the application of high pressure steam to the opposite ends of the piston valve 30 so that the piston valve is operated to apply steam at boiler pressure from the steam inlet 27 to opposite sides of the piston 23 in proper timed relationship to the reciprocal movements of the piston in cylinder 22 and to apply the exhaust from cylinder 22 to the second stage steam operated piston 34 reciprocable in second stage cylinder 35 in timed relationship to the reciprocating movements of piston 34, and to exhaust steam from second stage cylinder 35 through the exhaust steam channel 36 and exhaust outlet fitting 37. Second stage steam cylinder 34 is connected by a piston rod 38 to a second stage air compressing piston 39 which is reciprocable in the second stage air compressing cylinder 40. As the piston 39 works against pre-compressed air from cylinder 24 and the piston 34 is acted upon by low pressure steam exhausted from the first stage steam cylinder 22, piston 34 is materially larger than piston 39 in order to highly compress the air by the exhaust steam from the first stage steam cylinder.

The first stage air compressing cylinder 25 is provided with outlet valves 41 which control the passage of air from the first stage compressing cylinder into the second stage compressing cylinder and prevent any return of air from the second stage to the first stage cylinder and the second stage cylinder 40 is provided with air outlet valves 42 which control the passage of air from the second stage compressing cylinder 40 to the air outlet fitting 43 and through the pipe line 42 to the storage tank 11 and prevent return of air from the storage tank into the second stage compressing cylinder of the compressor. It is these outlet valves 41 and 42 which, when slightly worn, corroded, dirty or otherwise defective permit the leakage of air from the storage tank back into the compressing cylinders of the air compressor.

As the compressor 10 is of conventional and well known construction, a further description thereof is not considered to be necessary for the purposes of the present disclosure.

The steam valve 13 which controls the supply of steam to the steam operated portion of the air compressor comprises a hollow body 43 provided with an apertured partition 44, with an outlet fitting 45 connected to the adjacent end of the pipe line 14 and with an outlet fitting 46 connected by a suitable pipe line, not illustrated, to the steam dome of the locomotive boiler. A valve head 47 is secured on the lower end of a stem or plunger 48, the upper end of which is secured to a piston 49, reciprocable in a valve cylinder 50, the upper open end of which is closed by a removable cylinder head 51, which is centrally

apertured and provided with a tubular stud 52 screw threaded into such aperture. The piston and valve head are urged to the position illustrated in Figure 1, in which the valve head is displaced from the partition 44 to open the valve, by a compression spring 53 and the piston is moved to bring the valve head into engagement with the partition 44 and close the aperture through the partition by the pressure of compressed air in the chamber 54 between the piston and the cylinder head 51.

The governor 15 comprises two identical air pressure responsive units 55 and 55' pneumatically connected with chamber 54. The two units 55 and 55' are provided in order to provide brake air at two different pressures for different operating conditions of the locomotive. For example, the unit 55 may be a low pressure governor and set for an air pressure of one-hundred pounds per square inch, while the unit 55' may be a high pressure unit and set for an air pressure of one-hundred and thirty pounds per square inch. The two units are used alternatively depending upon the operating conditions under which the locomotive is being used and such two unit governors are usually provided only on freight locomotives which are used for long hauls with heavy and light trains and are also used for shifting and other operations. The selection of the units 55 and 55' is determined by operation of the manually controlled valves 56 and 57 provided in the conduits 16 and 17 between the respective units and the storage tank 11. As the two units 55 and 55' are substantially identical in construction and operation, a detailed illustration and description of only one is considered sufficient for the purpose of the present disclosure.

The unit 55 selected for detailed illustration, has a base 156 provided in its upper end with a chamber 157. An air inlet fitting 58 at one side of the base receives the adjacent end of the conduit 17 and communicates with the chamber 157. At its lower end the base is provided with a reduced, screw-threaded extension 59 received in a fitting 60 of the hollow bracket 61. The hollow bracket includes a chamber 62 which communicates through the tubular stud 52 with the chamber 54 in the valve piston head 51 and the base is provided with a bore 63 which extends from the chamber 157 to the chamber 62 and is restricted at its upper end. A needle valve plunger 64 is carried in the chamber 157 by a flexible diaphragm 65 in position to close the upper end of bore 63 and a compression spring 66 mounted in a spring cylinder 67 bears upon the upper side of the flexible diaphragm to resiliently maintain the valve plunger or needle 64 in closing relationship with the upper end of the bore 63. A spring abutment 68 is threaded into the upper end of the cylinder 67 and is adjustable in the cylinder to vary the loading on the spring 66 and thereby change the air pressure at which the governor unit is operative to close the valve 13. A removable cap 69 is secured to the upper end of cylinder 67 covering the abutment 68.

In operation, when the pressure of the air in tank 11 reaches a predetermined value and assuming that the valve 57 is open, this air pressure acts on the underside of flexible diaphragm 65 and raises valve plunger 64 off of its seat at the upper end of bore 63 so that air passes from the chamber 157 through the bore 63 into the chamber 62 and from the chamber 62 through the hollow stud 52 into the chamber 54 to force the piston 49 downwardly and close the steam valve.

This cuts off the supply of steam to the steam operated portion of the air compressor and discontinues operation of the compressor. As soon as the pressure in storage tank 11 falls below the predetermined pressure the spring 66 expands causing the valve plunger or needle 64 to close the upper end of bore 63 and cut off the supply of compressed air to the chamber 54. The base 56 is provided with a bleed opening 70 through which the air trapped below the valve plunger 64 escapes permitting the piston 49 to rise in its cylinder and the valve 13 to open under the influence of the compression spring 53 to again place the air compressor in operation.

A conduit 11 is frequently connected to one end of the hollow bracket 61 and extended into the cab where it is provided with a manually controlled valve 12 so that the engineer can discontinue operation of the governor and maintain the compressor in operation under emergency conditions, the storage tank 11 being provided, of course, with a suitable safety or blow-off valve, not illustrated.

The check valve 18 comprises a hollow, elongated cylinder 73 having at one end a dome-shaped end wall 14 provided with a central aperture 75 and having internal screw threads 76 near its opposite, open end. Intermediate its length the cylinder is provided with a transverse partition 71 having a central aperture 78 and a plurality of apertures 79 surrounding the central aperture.

A check valve stem 80 is slidable in the central aperture 78 of the partition and carries a valve disc 81 which seats on the side of the partition 71 adjacent the storage tank 11 to close the apertures 79, and thus prevent return flow of air from the tank to the compressor. The valve disc 81 is preferably a composite structure including a disc 82 of suitable resilient material, such as synthetic rubber, and a metal washer 83 overlying the major portion of the surface of the disc 82 opposite the partition 71.

An externally screw-threaded plug 84 is threaded into the open end of the cylinder 73 and provided with a screw-threaded central aperture which receives the adjacent end of the portion 85 of the pipe line 12 extending from the check valve to storage tank 11. This plug is provided at its inner side with a hollow, tapered boss 86 having its distal ends substantially parallel to the partition 71 and having a plurality of openings 87 in its wall.

The portion 88 of the pipe line 12 between the compressor outlet and the check valve has its end remote from the compressor received in the aperture 75 of the end wall of the cylinder 73. This end of the pipe line portion 88 is reduced at the location of the aperture and flared within the cylinder to direct jets of air from the compressor through the apertures 79 against the valve disc 81 to raise this valve disc and permit free flow of air through the check valve from the pipe line portion 88 to the pipe line portion 85. The boss 86 stops the upward movement of the valve disc and the air flows from the apertures 79 around the disc and through the openings 81 in the wall of boss 86 and into the portion 85 of the pipe line 12. When the compressor is not operating the disc 81 rests upon the partition 71 and closes the apertures 78 and 79 so that air cannot return through the check valve.

The construction of the check valve 18 is such that this valve will operate for an extended period of time, usually much longer than the period

during which the outlet valves 41 and 42 of the compressor are entirely leak proof. And even in the event of leakage of the valve 18, this valve can be removed and replaced by a new valve very quickly and easily and such replacement of the check valve will permit continued use of the compressor even though the compressor outlet valves are subject to some leakage.

The compressor unloading valve 19 comprises an elongated cylinder 90 having at one end a centrally apertured end wall 91 and having internal screw-threads 92 at its opposite, open end. An apertured plug 93 is threaded into the open end of the cylinder 90 and a valve plunger 94 comprising two spaced-apart valve pistons 95 and 96 connected by a rod or reduced portion 97 is reciprocable in the cylinder 90. A compression spring 98 is disposed in the cylinder between the valve piston 95 and end plug 93 to resiliently urge the valve plunger toward the end wall 91. The conduit 20 is connected at one end to the portion 88 of the pipe line 12 between the compressor outlet and the check valve 18 and is connected at its opposite end to the unloading valve 19 through an aperture 99 in the wall of cylinder 90 intermediate the length of the cylinder. The conduit 21 is connected at one end to the end wall 91 by a fitting 100 extending into the end wall aperture and is connected at its opposite end to the hollow bracket 61 in communication with the chamber 62.

When compressed air is admitted into the chamber 62 of the hollow bracket 61 through the bore 63 of the governor base, the pressure of this air is applied through the conduit 21 against the valve piston 95 of the unloading valve, forcing the valve plunger 94 toward the end plug 93 against the force of spring 98. The cylinder 90 is provided in its wall with a vent opening 101 disposed between the end plug 93 and the aperture 99 so that when the valve plunger 94 is forced toward the end plug 93, the valve cylinder connected end of conduit 20 is in communication with the vent aperture 101 to vent any compressed air from the compressor when operation of the compressor is stopped by closing of the steam valve 13.

This unloading of the compressor maintains the pressure in the air compressing cylinders of the compressor substantially at atmospheric pressure so that the steam pistons can easily move the air compressing pistons as soon as the steam valve 13 is open and the compressor will not stall.

The invention may be embodied in other specific forms without departing from the spirit or essential characteristics thereof. The present embodiment is, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

Having thus described my invention, what I claim as new and desire to secure by Letters Patent is:

1. In locomotive carried air compressing apparatus, a steam operated air compressor, an air storage tank pneumatically connected to the outlet of said compressor, a steam valve controlling the operation of said compressor, and an air operated governor operatively connected to said valve and pneumatically connected to

said air storage tank to close said steam valve when the air pressure in said tank reaches a predetermined value, a check valve disposed in the pneumatic connection between said storage tank and said compressor and arranged to prevent flow of air from said tank to said compressor while permitting free flow of air from said compressor to said tank, and a compressed air operated unloading valve pneumatically connected to said compressor outlet and to said air operated governor and operated by said governor upon steam valve closing operation of the governor to vent compressed air from said air compressor, said check valve comprising an elongated hollow cylinder having an open end and an apertured end wall at its other end and an apertured transverse partition therein intermediate its length, an apertured plug secured in the open end of said cylinder and having a hollow boss extending into said cylinder and spaced from said partition, said boss having openings in its wall, and a valve disc disposed between said partition and said boss and operative to close the apertures in said partition, said end wall receiving one end of the compressor connected portion of the pneumatic connection between said compressor and said storage tank and said plug receiving one end of the tank connected portion of such pneumatic connection.

2. In locomotive carried air compressing apparatus, a steam operated air compressor, an air storage tank pneumatically connected to the outlet of said compressor, a steam valve controlling the operation of said compressor, and an air operated governor operatively connected to said valve and pneumatically connected to said air storage tank to close said steam valve when the air pressure in said tank reaches a predetermined value, a check valve disposed in the pneumatic connection between said storage tank and said compressor and arranged to prevent flow of air from said tank to said com-

pressor while permitting free flow of air from said compressor to said tank, and a compressed air operated unloading valve pneumatically connected to said compressor outlet and to said air operated governor and operated by said governor upon steam valve closing operation of the governor to vent compressed air from said air compressor, said unloading valve comprising an elongated hollow cylinder having an open end and an apertured end wall at its other end, a conduit receiving aperture intermediate its length and a vent opening between said conduit receiving aperture and its open end, an apertured plug secured in the open end of said cylinder, a valve plunger slideable in said cylinder and having two spaced-apart valve pistons, and a compression spring between said valve plunger and said end plug, said unloading valve being pneumatically connected at said conduit receiving aperture with the outlet of said compressor and at said end wall aperture with said compressor governor, and said valve plunger being movable by compressed air from said governor to connect said conduit receiving aperture with said vent opening.
